UNITED STATES PATENT OFFICE.

HERBERT W. ALDEN, OF HARTFORD, CONNECTICUT, ASSIGNOR, BY MESNE ASSIGNMENTS, TO THE COLUMBIA MOTOR CAR COMPANY, OF HARTFORD, CONNECTICUT, A CORPORATION OF CONNECTICUT.

CARBURETER.

1,072,376.

Specification of Letters Patent. Patented Sept. 2, 1913.

Application filed April 15, 1905. Serial No. 255,712.

To all whom it may concern:

Be it known that I, HERBERT W. ALDEN, a citizen of the United States, residing at Hartford, in the county of Hartford, State 5 of Connecticut, have invented certain new and useful Improvements in Carbureters for Explosion-Engines, of which the following is a full, clear, and exact description.

My invention relates to that type of internal combustion engine in which the gasoline or other liquid fuel and the air for supporting combustion thereof are mixed before admission to the cylinder of the engine, and the improvements have more special reference to a means for regulating the air and fuel supply proportionately; and the invention has for its primary object to provide improved and efficient means whereby the speed of the engine may be governed or controlled without varying the proportions of air and explosive, by varying the amount of the explosive mixture admitted to the cylinder.

The laws governing the flow of liquids and gases through orifices are such that for low pressures, such as are found to exist in the carbureting or mixing chamber of a carbureter, they are practically identical, and it is upon this principle and the working out 30 of the necessary details to produce a carbureter operating upon these laws, that my invention is based. In all carbureters of this type which are now in use the flow of fuel through the nozzle is dependent not only 35 upon the suction of the engine, but in addition, upon a certain aspirating effect produced by the air passing over or about the fuel nozzle, and my invention has for its object the avoidance of this complexity of 40 causes producing a flow of fuel, so that the flow of both fuel and air may be subject to the above-mentioned law. To accomplish this, therefore, the aspiratory effect of the inflowing air upon the fuel must be eliminated, and it is readily seen that to obtain a 45 uniformly constant mixture under all conditions of speed (the speed of the engine producing variations in the amount of vacuum in the mixing chamber) it is absolutely essential to have the flow of air and the flow of fuel governed only by the amount of 50 vacuum in the carbureting space, so that there may be no variations in the propor-

tions of air and fuel passing through the carbureting space. The variation in the 55 vacuum existing in the carbureting space is a feature dependent entirely upon the speed of the engine and the amount of opening of the throttle, and therefore it forms an ideal controlling cause, and in my invention is 60 made the sole controlling cause of the flow of air and fuel. To bring about this result it is necessary to arrange the air inlet and the fuel inlet in such relative positions that there is no direct flow of air past the fuel 65 nozzle to produce an aspirating effect about the nozzle.

Referring now to the drawings in which similar characters of reference indicate corresponding parts in all the figures of the 70 drawings; Figure 1 represents the carbureter B connected in the usual manner with the cylinders A and A' of a motor such as may be mounted in a motor vehicle or motor boat as diagrammatically shown. Fig. 2 75 shows a section of the carbureter B on an enlarged scale. Figs. 3 and 4 illustrate two of the many modified forms of construction which might be used to embody the principles of my invention.

In Fig. 2, the carbureter B is shown as having a carbureting space, which for convenience I will call a chamber, to which leads an air inlet C. A fuel nozzle D is connected in any suitable way to the supply chamber E, and serves as a fuel inlet to the carbureting chamber. In this figure, I have shown walls extending from the air inlet into the carbureting chamber, said walls extending to a point adjacent the 85 fuel inlet, and aid in the mingling of the fuel supply with the air passing into said carbureting chamber. H is a hood or shield herein shown as an inverted cup, which is supported directly over the nozzle D and shields the same from the passing air. The casing is cut away at M to form a pocket, which extends underneath the hood H and aids in bringing the fuel supply into contact with the past-rushing air.

The usual passages I, J, are provided for circulating fluid for the regulation of temperature if desired. The air and fuel are drawn in by the suction of the engine as in other carbureters of this type, and are intimately mixed in the carbureting chamber

and passed into the combustion chamber of the motor in the usual manner, and it is not necessary to further describe the further action, which is well-known in the art.

5 There are, of course, many different ways of constructing the carbureter to bring about the results described and claimed, and I have chosen to illustrate certain simple constructions which effect the desired 10 result, but I do not limit the invention to the precise constructions shown, but claim broadly the invention on which the constructions shown are based, which invention is clearly set forth in the specification and 15 claims. It is known that many others have tried to produce a carbureter in which a uniformly constant mixture is obtained, and many have claimed to have attained the desired results, but it is again pointed out 20 that none of these carbureters have been so constructed that the flow of the fuel and air have been subject to only one controlling cause, such as is embodied in this invention, and therefore they must have 25 failed in their object of supplying always a definite proportion of air and fuel, which is absolutely essential.

What I claim is,—

1. In a carbureter, a carbureting chamber, a fuel inlet including an orifice free to supply fuel subject solely to suction, leading to said chamber, an air inlet and mixture outlet leading to said chamber, means in said chamber to shield the oil orifice and 35 to deflect the passing air from the oil orifice.

2. In a carbureter, a carbureting chamber, a fuel inlet free to deliver fuel subject solely to suction leading to said chamber, 40 an air inlet and a mixture outlet leading to said chamber, a shield intermediate the air inlet and the mixture outlet, whereby the fuel inlet is protected from the influence of the moving air, said chamber having a 45 pocket adjacent said shield for bringing the fuel supplied into contact with past-rushing air.

3. In a carbureter, a carbureting chamber, a valveless fuel-delivering nozzle projecting into said chamber, an air inlet leading to said chamber, means in said chamber for shielding said nozzle, and walls projecting into said chamber, adapted to effect 50 a mingling of the fuel supply with the passing air.

4. In a carbureter, a carbureting chamber, a valveless fuel inlet and an air inlet, leading to said chamber, and so disposed relatively that the flow of fuel is entirely 55 dependent upon the vacuum in the carbure-

ter, means adjacent to said fuel inlet to screen it from the inrushing air.

5. The combination in a carbureter, having a valveless fuel inlet and an air inlet, of a shield to prevent the air flowing directly 65 past the fuel inlet.

6. The combination in a carbureter, having an upwardly directed fuel inlet, a shield disposed so that the fuel admitted may impinge against it, an air inlet above 70 the shield, whereby the air is prevented from impinging against the fuel as it is emitted from the fuel inlet.

7. The combination in a carbureter, having a valveless fuel inlet and an air inlet, 75 of an inverted cup surrounding the fuel inlet, whereby flow of fuel by aspiration is prevented.

8. The combination in a carbureter, having a valveless fuel inlet and an air inlet, 80 of a shield surrounding the fuel inlet to prevent the flow of air past the fuel inlet.

9. The combination in a carbureter having an upwardly directed fuel inlet, an air inlet and a shield so arranged over said fuel 85 inlet that the fuel emitted may impinge on the inside of said shield, and the incoming air prevented from impinging against the stream as it leaves the fuel inlet.

10. In a carbureter, a carbureting chamber, walls in said carbureting chamber constituting an air inlet passing partially through said carbureting chamber and to a fuel inlet, walls in said chamber to deflect the air leaving the air inlet whereby the air 95 and fuel, as a mixture, is directed through said carbureting chamber.

11. In a carbureter, a carbureting chamber, a fuel inlet at the bottom of the chamber, an air inlet at one side and partitions 100 carrying said air toward the bottom of said chamber and around said fuel inlet, a deflector to prevent said air from impinging upon the fuel inlet.

12. In a carbureter, a carbureting chamber, an outlet from said carbureting chamber, a valve controlling said outlet, an air inlet to said chamber from one side having a partition in said chamber deflecting the air to the bottom thereof, a fuel inlet having wall portions so disposed as to deflect the air when it comes in contact with the fuel and passes the extremity of the air inlet partition.

This specification signed and witnessed 115 this 10th day of April, A. D. 1905.

HERBERT W. ALDEN.
